UNITED STATES PATENT OFFICE.

GOTTLOB BINDER, OF ROCHESTER, NEW YORK, ASSIGNEE TO AMERICAN LAUNDRY MACHINERY CO., OF CINCINNATI, OHIO, A CORPORATION OF OHIO.

BOSOM-PRESS.

1,336,415,

Specification of Letters Patent. Patented Apr. 13, 1920.

Application filed March 17, 1915. Serial No. 14,910.

To all whom it may concern:

Be it known that I, GOTTLB BINDER, of Rochester, in the county of Monroe and State of New York, have invented certain new and useful Improvements in Bosom-Presses; and I do hereby declare the following to be a full, clear, and exact description of the same, reference being had to the accompanying drawings, forming a part of this specification, and to the reference-numerals marked thereon.

My invention has for its primary purpose to afford a new method of ironing shirt bosoms, and in connection therewith to improve the construction of ironing machines of this class embodying generally a pair of ironing members such as a bosom supporting board and a heated chest with means for imparting relative movement to bring the heated chest into pressing relation with the board, and the improvement consists generally in so constructing the parts as to obviate the necessity of lapping one portion of the bosom over the other during the ironing operation, at the same time efficiently accomplishing the results and giving the desired finish to the garment. A further object is to simplify the operation of applying a shirt to the board, thus increasing the speed and general efficiency of the machine. To these and other ends the invention consists in certain improvements and combinations of parts, all as will be hereinafter more fully described, the novel features being pointed out in the claims at the end of the specification.

In the drawings:

Figure 1 is a side elevation of one embodiment of the invention;

Fig. 2 is a plan view showing the board with a shirt applied thereto;

Fig. 3 is a transverse sectional view, and

Fig. 4 is a plan view of the machine.

Similar reference numerals in the several figures indicate the same parts.

One of the chief difficulties encountered in bosom ironing machines has been that of properly ironing both surfaces of the two parts of a sectional bosom such as found in an open front shirt. If the parts of the bosom are permitted to overlap, assuming the same general relation as when worn, the under surface of the overlapping portion of the upper lap or section of the bosom will

not be ironed by reason of its engagement

with the upper surface of the overlapping portions of the under lap or section. This has been overcome in some instances by the insertion of a thin metal plate between the overlapping portions of the bosom which serves to impart a finish to the upper and under surfaces of the overlapping portions of the under and upper laps or sections respectively. I accomplish the same result without the use of a separate plate, thus reducing the time required by the operator in positioning a shirt and otherwise simplifying the ironing of this part of a garment. According to the method of the present application, the sections or laps of the bosoms are disposed substantially in spaced relation to each other, that is to say, they are entirely separated with the exception of small portions adjacent to the neckband, the latter being held by an expanding mechanism, and by the present improvement, the overlapping portions just referred to, adjacent to the front of the neckband, are reduced to a minimum, and are so small as to be negligible. The board on which the bosom rests is constructed so as to permit the two sections of the bosom to be arranged with their adjacent edges in diverging relation, as shown in Fig. 2, with the result that both the entire upper and lower surfaces of the bosom sections are completely ironed.

In the arrangement of parts which I have shown for carrying out the present method, 1 designates a heated chest to which steam or other heating medium is supplied through a pipe 2 in the usual manner, characteristic of this class of machinery. 3 is a support on which is mounted the ironing board 4 provided with a padded covering 5. The board 4 is of such a contour as to permit the parts of a sectional bosom to be disposed in spaced relation to each other, and to this end is constructed wider than the bosom, being preferably tapered from its lower end toward its upper end, the widest part of the board being adapted to receive the lower part of the bosom, as shown in Fig. 2, and the heated chest or upper ironing member is preferably of a contour corresponding to that of the ironing board, although this is not essential as long as the heated chest is brought into engagement with every part of the bosom. The ironing board may be provided with neckband retaining and expanding means comprising

- stationary blocks 6, movable blocks 7 and flexible band 8, all of which form no part of the present invention, and is a well known structure in this art. Further, the board 5 carries the usual tail clamping means such as designated at 9, and operating to stretch the parts of the bosom and hold them taut until the board is brought into pressing relation with the heated chest.
- 10 In positioning a shirt, the neckband is first secured in position and the neckband clamping devices brought into operation. Thereupon, the operator stretches the two parts of the bosom by engaging the tail 15 portions of the shirt and in this stretching process the two sections are drawn on converging lines, so that they are arranged substantially as shown in Fig. 2 with their adjacent edges in diverging relation, and when 20 thus positioned the tail clamping mechanism 9 is operated to hold the bosom in proper relation. With such an organization and method of ironing, the difficulty of ironing over overlapping portions is obviated and 25 the buttons of the shirt are not subjected to excessive pressure. The speed of operation of the machine is increased by my improvement, and the garment can be finished as nicely as may be desired.
- 30 I claim as my invention:
1. A machine for ironing open front shirts with the front portions spread in diverging relation, said machine including relatively movable ironing chest and board members, said board member increasing in width from the neck band end toward the tail end and at the neck band end having the proper width to fit within the upper portion of a small size shirt without distorting its front portions, and an adjustable neckband support located adjacent the neck band end of said board member.
  2. A machine for ironing open front shirts with the front portions spread in diverging relation, said machine including relatively movable ironing chest and board members, said board member increasing in width from the neck band end toward the tail end and at the neck band end having the proper width to fit within the upper portion of a small size shirt without distorting its front portions and toward its tail end having the proper width to permit sufficient divergence of the shirt front portions without distortion, and an adjustable neckband support located adjacent the neck band end of said board member.

GOTTLOB BINDER.
